UNITED STATES PATENT OFFICE.

ROGER A. SIMONSON, OF BERWYN, ILLINOIS.

CARD-RECEPTACLE.

SPECIFICATION forming part of Letters Patent No. 686,358, dated November 12, 1901.

Application filed May 6, 1901. Serial No. 58,954. (No model.)

To all whom it may concern:

Be it known that I, ROGER A. SIMONSON, a citizen of the United States, residing at Berwyn, in the county of Cook, State of Illinois, 5 have invented a new and useful Improvement in Card-Receptacles, of which the following is a specification.

My invention relates to card-receptacles designed for use as card-catalogues and the like, 10 more especially of the class wherein the cards are retained in position in the box or tray by means of folding retaining-rods, an example of this form of retaining-rod being set forth in Letters Patent of the United States No. 15 671,454, issued to me April 9, 1901.

My present invention has for its object the providing of advantageous means for operating such retaining-rods, said object being accomplished by the mechanism illustrated in 20 the accompanying drawings, in which—

Figure 1 is a plan view of a card-receptacle embodying my invention. Figs. 2 and 3 are views thereof in elevation, taken in section on the line 2 2, Fig. 1, and looking in the 25 direction of the arrows adjacent to said line, Fig. 2 showing the leaves of the retaining-rod in a spread or open position and Fig. 3 showing said leaves folded. Figs. 4 and 5 are views drawn to greatly-enlarged scale, 30 taken chiefly in vertical section lengthwise through the axis of the folding retaining-rod, Fig. 4 showing the vertical controlling-rod in its highest position with the leaves of the retaining-rod folded and Fig. 5 showing said 35 controlling-rod in its lowest position and rotated through an angle of ninety degrees from the position thereof shown in Fig. 4. In Fig. 5 the leaves of the retaining-rod are spread, consequent upon the depressed position of 40 said controlling-rod. Fig. 6 is a detail side elevation of the upper section of the controlling-rod. Fig. 7 is a detail view of said upper section, as in Fig. 6, showing the same axially rotated through an angle of ninety 45 degrees from the position shown in Fig. 6. Figs. 8 and 9 are detail sectional views of said upper section of the controlling-rod and adjacent parts, said figures being taken in plan on the lines 8 8 and 9 9, respectively, Fig. 5. 50 Fig. 10 is a perspective view showing the operating device adapted to an alternative form of folding retaining-rod. Fig. 11 is a plan

view of a portion of the folding rod of the type as in Fig. 10, showing the end bearing thereof.

Similar letters refer to similar parts throughout the several views.

The tray or receptacle comprises the bottom portion *a*, sides *b b*, and front and rear walls *c* and *d*, respectively. The pintle *e* is 6c supported in said front and rear walls *c* and *d* and forms the hinge or axis of the leaves *ff* of the card-retaining rod.

At the front of the receptacle the arms *g g* are rigidly secured to the said leaves *f* and 65 are operated to fold and spread said leaves by means of the links *h h*, said links being pivotally connected at one extremity to the free extremities of the said arms *g*. The extremities of the links *h* opposite to the arms 70 *g* are pivotally secured to the lower section or length *i* of the controlling-rod by means of the pin *j*. Said section *i* is designed to travel in the vertically-arranged chamber *k*, located in the front wall *c* of the receptacle. The 75 slot *m*, which extends from said chamber *k* to the rear surface of the front wall *c*, accommodates the rearwardly-projecting pin *j*, above described. The parts are so related that the vertical travel of the lower section *i* 80 of the controlling-rod, acting through the agency of the pin *j*, links *h h*, and arms *g g*, results in the operation of the leaves *f f* of the folding retaining-rod.

The spiral compression-spring *n* is supported at the lower extremity of the chamber *k* and bears against the pin *j* of the rod-section *i* in such a manner as to tend to keep 85 said rod-section *i* at the uppermost position thereof, at which time the leaves *f f* will be 90 folded, as shown in Fig. 3.

The upper extremity of the rod-section *i* is convex and adapted to fit into the correspondingly concave lower extremity of the upper section or length *o* of said controlling-rod. 95 At the lower extremity also of said rod-section *o* is located a conical portion *p*, which may be seated upon the corresponding conical portion *q* of the preferably metallic socket or thimble *r*. Said socket *r* is open at its 100 lower extremity and is arranged vertically in said front wall *c* in such a manner as to communicate with the upper extremity of the chamber *k*. Near the upper extremity of

said socket, which is open and preferably flush with the upper edge of the front wall *c* of the receptacle, is the pin *s*, which is fixed in said front wall and extends through said 5 socket a short distance into the interior of the latter. The said upper section *o* of the controlling-rod terminates at its upper extremity in the milled head *t*, which is designed to be grasped by the operator. The 10 main body of the said rod-section *o* is approximately cylindrical and preferably of a length equal to that of the socket *r*, said socket forming a guide wherein said rod-section may freely rotate about its axis and also 15 travel freely in a vertical direction. Near its upper and lower extremities said rod-section *o* has the circumferential grooves *u* and *v*, respectively, adapted to receive the inwardly-projecting extremity of the above- 20 described pin *s*. When said pin *s* is in engagement with either one of said grooves *u* or *v*, the vertical travel of the rod-section *o* is prevented. In order, however, to render it possible for said rod-section *o* to be moved 25 vertically, a portion of said rod-section is cut away, leaving the preferably plane surface *w* extending from one to the other of said grooves and constituting a slideway for receiving said pin *s*. The parts are so designed 30 that when said pin *s* is in engagement with either of said grooves the section *o* may rotate, but is prevented from moving vertically, and when said pin is in conjunction with the 35 said surface *w* said section *o* may travel vertically, but is prevented from rotating upon its axis.

The pins *xx* are set within the grooves *u* and *v*, so as to engage the inner portion of the pin *s* and form a stop, whereby the section *o* 40 is prevented from making a complete revolution.

The chief purpose in constructing the controlling-rod in two sections and providing a ball-and-socket or a conical joint at the junction 45 is to permit the independent rotation of said parts and at the same time enable one of said parts to transmit motion to the other of said parts in a lengthwise direction.

In operation when the controlling-rod is in 50 its highest position, as shown in Fig. 4, the section *o* is prevented from further rising by means of the pin *s*, which abuts against the shoulder formed by the groove *v* at the lower extremity of said upper section. Under this 55 condition the rod-section *i* and pin *j* are held aloft and the leaves *ff* of the retaining-rod are folded together. When it is desired to spread said leaves, the rod-section *o* is rotated until the slideway *w* thereon comes opposite 60 to the pin *s*, at which time the entire controlling-rod is free to be moved downward by the operator against the force of the spring *n*. When said controlling-rod has reached the 65 lower extremity of its travel, so that the conical lower portion *p* of the section *o* becomes seated in the portion *q* of the thimble *r*, the groove *u* comes opposite to the pin *s*. The

rotation of said section *o* causes said groove *u* to become engaged by said pin, thereby preventing the travel of said controlling-rod and 70 causing the leaves of the retaining-rod to remain in a spread condition.

My present invention is not particularly concerned with the construction of the retaining-rod, for folding rods of various types may 75 be used. For example, my present operating device may be applied to a folding rod which is not hinged along the edges thereof, but at the extremities merely. This latter form of retaining-rod is shown in Figs. 10 and 11, and, 80 referring to said figures, *yy* represent the leaves, which have at the extremities of their adjacent edges the longitudinally-projecting and preferably cylindrical trunnions *zz*. Said trunnions are adapted to bear in the 85 front and rear walls of the receptacle and operate to hinge said leaves together. The links *hh* are in this alternative form shown as being pivotally connected directly to said leaves *yy*; but it is obvious that the connection may 90 be made through the medium of arms fixed to said leaves *yy* after the manner shown in connection with the previously-described form of retaining-rod. The operation of this 95 alternative form of rod is similar to the operation of the first-described form, the depressing of the controlling-rod causing the spreading of the leaves *yy* and the rising of said controlling-rod permitting the closing or folding thereof.

It is evidently not essential that a spring be employed to raise the vertical controlling-rod, for the same may be raised by hand. In this latter case a positively-connected swivel-joint of any ordinary pattern would be substituted for the cup-joint shown in the drawings.

Other variations of construction will present themselves to those skilled in the art, and I do not limit myself to the precise arrangement and construction herein shown.

What I claim as new, and desire to secure by Letters Patent, is—

1. In a card-receptacle, a plurality of members extending in the same direction and having substantially contiguous adjacent edges, said members constituting a folding retaining-rod; in combination with a linkwork connected to said members for operating the same and a vertical reciprocating rod connected to 110 said linkwork for operating the same.

2. In a card-receptacle having a folding retaining-rod, the combination of links connected to the leaves of said rod, a reciprocating member connected to said links for 115 operating said folding rod, and means for detaining said reciprocating member at different points in the travel thereof to thereby maintain the folding rod in a spread or folded position.

3. In a card-receptacle having a folding retaining-rod, the combination of links connected to the leaves of said rod, a reciprocating member connected to said links for 130

operating the same, a spring operating upon said reciprocatory member for moving the same in one direction, and means for retaining said reciprocatory member against the 5 force of said spring.

4. In a card-receptacle having a folding retaining-rod, the combination of links connected to the leaves of said folding rod, a controlling-rod section connected to said links 10 for operating the same, a spring acting upon said controlling-rod section to force the same in an upward direction to fold said rod, an upper controlling-rod section adapted to force said lower rod-section in a direction against 15 the force of said spring, a pin for engaging said upper rod-section to detain the same and means upon said upper rod-section for engagement with said pin, to prevent the motion of said rod in a vertical direction.
- 20 5. In a card-receptacle, a circumferentially-grooved upper rod-section, a lower rod-section, said upper and lower sections comprising a vertically-movable controlling-rod, a folding retaining-rod, the leaves whereof are 25 connected to and operated by the lower section of said controlling-rod, a detaining-pin secured to said receptacle and adapted to engage the circumferentially-grooved upper section of said controlling-rod, and connections 30 between said upper and lower sections of said controlling-rod, whereby said upper section is revolvable independently of said lower section.
6. In a card-receptacle a lower and an upper controlling-rod section connected by a 35 ball-and-socket or similar joint, said sections

constituting a vertically-arranged controlling-rod and the upper section being provided with a pair of circumferential grooves, a spring acting upon the lower rod-section to 40 force the same in an upward position, a pin fixed in said receptacle for engaging said circumferential grooves in the upper section of said controlling-rod, said upper section having a slideway connecting the circumferential 45 grooves therein, a folding retaining-rod, and connections between the leaves of said rod and said lower controlling-rod section for operating said folding retaining-rod.

7. In a card-receptacle, a socket or thimble 50 secured in the front wall of the receptacle, a controlling-rod, the upper section whereof is provided with a milled head and circumferential grooves connected by a slideway, said upper section traveling within said socket or 55 thimble, a pin fixed in said front wall and adapted to enter the circumferential grooves in said upper section for preventing the vertical travel of the latter, the lower section of said controlling-rod being connected to said 60 upper section by a cup-joint; a spring operating upon said lower section to force the same in an upward direction, a pin connected to said lower section, a slot in said front wall for accommodating the motion of said pin, links 65 pivotally attached to said pin, and a folding retaining-rod connected to and operated by said links.
